UNITED STATES PATENT OFFICE

GEORGE W. WAGNER, OF MARLINTON, WEST VIRGINIA

RAIL JOINT

Application filed July 16, 1931. Serial No. 551,217.

This invention aims to provide a rail chair which will have unusual strength against downward flexure at the meeting ends of the rails, it being possible to locate the bolts properly, and adequate provision being made for spiking the chair to the tie.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:

Figure 1 shows in side elevation, a device constructed in accordance with the invention;

Figure 2 is a section on the line 2—2 of Figure 1;

Figure 3 is a section on the line 3—3 of Figure 2.

The device comprises, in a rail joint, a chair including a base plate 1 having oppositely disposed overhanging wings 2 provided on their inner edges with upwardly extended walls 3 having bolt holes 4. Rails are provided, and have their ends received in the chair, the combined thickness of the walls 3 and the web 5 of the rails approximating closely the width 6 of the ball 7 of the rails, to give the walls 3 strength to withstand downward flexure.

The chair is provided with outwardly projecting integral buttresses 8 which extend, from the outer edges 9 of the base plate 1, upwardly and inwardly, as at 10, across the wings 2, and upwardly, as at 11, along the walls 3. The buttresses 8 are located at the end surfaces 12 of the rails, the upper ends of the buttresses being spaced, as at 14, from the upper edges of the walls 3, to leave room for wheel flanges.

Inner bolts 15 and outer bolts 16 are lo-

cated in the bolt holes 4 of the walls 3 and engage the webs 5 of the rails. The buttresses 8 taper, as at 17, in width, as they extend upwardly, thereby to permit the inner bolts 15 to be disposed sufficiently close to the end surfaces 12 of the rails. Those parts of the outer edge portions of the base plate 1 which lie on opposite sides of the buttresses 8 constituting spike flanges 18 having notches 19 to receive the spikes 20 which hold the chair on the tie 21.

The chair has been designed with the specific view of making it unusually strong immediately below the end surfaces 12 of the rails, and this is accomplished by means of the buttresses 8, and by thickening the walls 3, so that the combined width of the walls 3 and of the web 5 will approximate the width 6 of the ball 7. The tapering of the buttresses, at 17, permits the inner bolts 15 to be located properly. There is no chance that the wheel flanges will strike the buttresses 8, and the flanges 18 afford a means whereby a chair may be spiked down. Because the buttresses 8 extend outwardly to the extreme outer edges 9 of the base plate 1, the inner ends of the spike flanges 18 are connected to the wings 2, the spike flanges being reinforced accordingly.

Having thus described the invention, what is claimed is:

In a rail joint, a chair comprising a base plate having oppositely-disposed overhanging wings provided on their inner edges with upwardly-extended walls having inner and outer bolt holes, the chair being provided, on each side, with a single outwardly-projecting integral buttress located midway between the inner bolt holes, at equal distances from the outer bolt holes, and at equal distances from the ends of the base plate, the buttresses extending inwardly from the extreme outer edges of the base plate, upwardly and inwardly across the wings, and upwardly along said walls, the upper ends of the buttresses being approximately flush with the upper edges of the inner bolt holes and being spaced from the upper edges of said walls, enough to leave room for wheel flanges, the buttresses tapering in width as they extend upwardly, so that the inner bolt holes can be located close to-

gether and at the same time have the buttresses afford a maximum amount of reinforcement at their lower, outer ends, and having upper ends of considerable width, compared with the distance between the inner bolt holes, those parts of the outer edge portions of the base plate which lie on opposite sides of the buttresses constituting spike flanges having spike notches, all of which are disposed beyond the ends of the buttresses, the outer edges of the buttresses and the outer edge of each spike flange being disposed in the same straight line with the outer edge of one buttress.

In testimony that I claim the foregoing as my own, I have hereto affixed my signature.

GEORGE W. WAGNER.
